SWITCH TERMINAL

Filed March 5, 1925

Inventor:

Monroe Guett.

by his Attorneys:
Hoover & Hooson

UNITED STATES PATENT OFFICE

MONROE GUETT, OF HARTFORD, CONNECTICUT, ASSIGNOR, BY MESNE ASSIGNMENTS, TO THE ARROW-HART & HEGEMAN ELECTRIC COMPANY, OF HARTFORD, CONNECTICUT, A CORPORATION OF CONNECTICUT

SWITCH TERMINAL

Application filed March 5, 1925. Serial No. 13,416.

One object of this invention is to construct a snap switch terminal, in which the contact plates have the desired resiliency with a comparatively limited extension beyond the post.

5 A further object of the invention is to provide a simple and effective means for assembling and holding the plates on the post.

A still further object of the invention is to provide means for clamping a wire to the 10 post.

In the accompanying drawings:

Fig. 1 is a sectional elevation of a snap switch showing my improved switch terminals in position, the section being on the line 15 1—1, Fig. 2;

Fig. 2 is a plan view with the casing in section;

Fig. 3 is an enlarged sectional view of one 20 of the switch terminals on the line 3—3, Fig. 2;

Fig. 4 is a sectional view on the line 4—4, Fig. 2;

Fig. 5 is a sectional plan view on the line 5—5, Fig. 4;

25 Fig. 6 is a perspective view of one of the switch terminals;

Fig. 7 is a detached perspective view of one of the contact plates; and

Fig. 8 is a view illustrating a modification of the invention.

The base 1 is preferably made of porcelain, or other non-conducting material. The snap switch mechanism 2 can be of any suitable construction so that the blades 3 "snap" as 35 they pass from one terminal to the other, when the handle 4 is turned.

In the present instance there are four 40 switch terminals, and each one consists of a post 5, on which are mounted the spring contact plates 6 that are made as illustrated in Fig. 7. Each post 6 is secured to the base 1 by screws 7, or other suitable fastenings, Fig. 3, and is made tubular for the passage of the conducting wire *a*, which is held to the 45 post by a hollow, tapered screw plug 8 that is threaded to engage the internal threads of the post. The posts are preferably threaded beyond the threaded portion as shown in Figs. 3 and 4, so that the tapered plugs readily enter the reduced openings in the posts.

Each plug is split longitudinally to form jaws, as illustrated in Figs. 4 and 5, so that, when a plug is screwed into a post, the jaws are contracted upon the wire *a*, whereby the wire is held rigidly to the post, which makes 55 a good electric contact.

Each post 5 has two or more annular grooves 9, in which are located the laterally extended ends 10 of the contact plates. Each contact plate is bent at 11, as shown in Fig. 7, to provide a long spring element, which extends back of the center line of the post. The end portions 10 of the plates are parallel with the body of the contact plate, but are separated therefrom to allow the plate to have the desired flexibility. The plates are forked and curved to fit the posts and are turned up at each edge, as at 12, to allow the switch blades to pass readily into the space 60 between the plates. 65

Each extended end 10 of a contact plate is notched at 13, and each post is slotted, as at 14. The notches of the plates are brought into alignment with the slots, and rods 15 are driven into the slots, locking the contact 70 plates in proper position on a post. 75

This construction makes an effective, yet simple means for attaching the plates to the posts.

In Fig. 1, both contact plates are spring 80 plates. In some instances, one plate may be a spring plate and the other may be a rigid plate, which is secured to a post, as in Fig. 8, which illustrates a modification in which three plates are mounted on the post 5^a. 85

The upper and lower plates 6^a are spring 90 plates, which are made in the manner shown in Fig. 7. The intermediate plate is a flat, rigid plate, which has notched, extended ends that fit a groove in the post and are secured to the post by the rod 15^a.

I claim:

1. The combination in a switch terminal, of a post having a groove therein; two contact plates, one of said plates being forked to span the post, the forked ends being bent upon themselves to form a long spring member and two short spring members extending back of the centre line of the post to provide an extended spring contact plate, 100

the short members of the plate having lateral extensions located in the groove in the post; and means for retaining the said short members to the post.

5 2. The combination in a switch terminal, of a post having a groove therein and having slots intersecting the groove; two contact plates, one of said plates having portions at each side of the post bent to form long and short spring members, the short side members of the plate being notched and extending into the groove; and rods located in the slots of the post and extending through the notches in the plate,

10 15 retaining the plate in position.

3. The combination in a switch terminal, of a post having two annular grooves therein and having a vertical slot intersecting the grooves; two spring contact plates shaped to 20 span the post, the side portions of each spring plate being bent upon themselves to form long and short spring members, and short portions having lateral extensions located in the grooves of the post, one extension of 25 each plate being notched; and a rod located in the slot of the post and extending through the notches in the plates.

4. A terminal plate for an electric switch, said plate being made of spring metal and 30 forked to span a post, the ends of the forked portions of the plate being bent over the body of the plate to form short attaching members and an extended spring member, the short members having lateral extensions ar-

35 ranged to engage a post.

5. A terminal plate for an electric switch, said plate being made of spring metal and forked to span a post, the ends of the forks being bent over the body of the plate to form 40 attaching members on a different plane from the body of the plate.

MONROE GUETT.
